UNITED STATES PATENT OFFICE.

WILLIAM C. ANDERSON, OF TOLEDO, OHIO, ASSIGNOR TO THE AMERICAN CUT GLASS COMPANY, OF CHICAGO, ILLINOIS.

DESIGN FOR A GLASS DISH.

SPECIFICATION forming part of Design No. 27,063, dated May 18, 1897.

Application filed March 20, 1897. Serial No. 628,547. Term of patent 7 years.

To all whom it may concern:

Be it known that I, WILLIAM C. ANDERSON, of Toledo, county of Lucas, and State of Ohio, have invented a certain new and original De-

sign for a Glass Dish; and I do hereby declare that the following is a full, clear, and exact description of the invention, which will enable others skilled in the art to which it appertains to make and use the same, reference being had to the accompanying drawings, and to the figures of reference marked thereon, which form part of this specification.

This design relates to a glass dish, and particularly to the ornamentation of the exterior surface thereof.

The drawings represent, in Figure 1, a bottom plan view of a dish containing the design, and in Fig. 2 a section on lines *x-x*, Fig. 1.

20 The design is applicable to dishes, plates, and bowls.

The leading features of my design are a central prismatic stud surrounded by a six-pointed star, with an inscribed six-pointed

25 star whose points contact with the star of larger area intermediate the points thereof, with six conoidal projections extending to the margin of the dish.

Embellished with curved lines extending 30 from the body of the star to near the margin of the dish and meeting to form conoids, there being two prismatic studs in each conoid, with triangular lines forming prisms, and within each conoid are kite-shaped fields with a

prismatic stud at each apex and crossed lines 35 in the field, with a checkering at each lower point, each point of the star of greatest area having diamond-shaped prisms.

1 designates the central prismatic stud, 2 the star of greatest area, and 3 the inscribed 40 star of less area. 4 designates conoidal projections extending to the margin of the dish, and 5 conoidal lines extending from the body of the star 2 to near the margin, thus describing 45 six conoids, each of which is embellished with two prismatic studs 6, with triangular lines radiating therefrom, forming prisms. Within each conoid are kite-shaped fields 7, each having a prismatic 8 at the apex and crossed lines 9 in the field, with a checkering 50 in each lower point. Each point of star 2 is embellished with diamond-shaped prisms.

The conoidal lines and inclosed prismatic studs, with the kite-shaped fields and prismatic studs at the apex, together with the 55 crossed lines forming prisms and checkering of the points of the star, lend a pleasing effect to the design.

What I claim is—

The design for a glass dish, substantially as 60 shown and described.

In testimony that I claim the foregoing as my own I hereby affix my signature in presence of two witnesses.

WILLIAM C. ANDERSON.
